UNITED STATES PATENT OFFICE.

JOHN H. SHAW, OF NEW HAVEN, CONNECTICUT, ASSIGNOR TO SARGENT & COMPANY, OF NEW HAVEN, CONNECTICUT, A CORPORATION OF CONNECTICUT.

LOCK.

1,229,332.

Specification of Letters Patent. Patented June 12, 1917.

Application filed January 29, 1914. Serial No. 815,229.

To all whom it may concern:

Be it known that I, JOHN H. SHAW, a citizen of the United States, residing in the city and county of New Haven and State of Connecticut, have invented certain new and useful Improvements in Locks, of which the following is a full, clear, and exact description.

This invention relates to locks, and more particularly to locks in which a pin tumbler lock mechanism is housed in a knob, and wherein both the knob and the pin tumbler lock are employed to operate a suitable bolt, such as a latch bolt. The pin tumbler lock is operative on the bolt at all times when the proper key is used, but the knob may be dogged by suitable mechanism in order to confine operation of the bolt from the outside to the key mechanism alone.

Heretofore the pin tumbler lock mechanism has usually been rigidly connected with the knob shell so as to rotate therewith when the knob is turned, and the pin tumbler lock is secured to the escutcheon, or to the casing containing the bolt mechanism only through the intermediary of the rotary knob spindle. By my improvements, however, the pin tumbler lock is rigidly and fixedly secured to the escutcheon just as in the case where no inclosing knob is employed, and the knob, or at least the major portion of the same, rotates about the pin tumbler lock, on which it has a suitable bearing.

The primary objects of my invention are to provide an efficient knob lock constructed along the lines above indicated; to furnish a structure in which the cap piece of the knob contains the pin tumbler lock and is fixed to the escutcheon to form a bearing for the rotatable part of the knob; to provide a construction in which the knob spindle holds the key rod in place relatively to the key barrel or plug; to furnish a lock in which the means for securing the pin tumbler lock to the escutcheon also serves to secure the knob thimble to the escutcheon; and to generally improve the construction and operation of devices of the class to which my invention relates.

To these and other ends, the invention consists in the novel features and combinations of parts to be hereinafter described and claimed.

In the accompanying drawings, Figure 1 is a front elevation of a knob lock embodying my improvements. 55

Fig. 2 is a side elevation of the same.

Fig. 3 is a fragmentary inner face view of the escutcheon to which the knob is applied. 60

Fig. 4 is a section on line 4—4 of Fig. 1.

Fig. 5 is a section on line 5—5 of Fig. 1.

Fig. 6 is a section on line 6—6 of Fig. 4.

Fig. 7 shows the several parts of the knob lock in the relation wherein said parts are assembled. 65

Fig. 8 is a rear elevation of the cap piece for the knob, and of the pin tumbler lock mechanism carried thereby.

Fig. 9 is a front elevation of the knob shell detached. 70

Fig. 10 is a rear elevation of Fig. 9, and Fig. 11 is a detail of the thimble.

Referring to the drawings, my improved knob comprises in its general features a cap piece 20 carrying the pin tumbler lock 21 and fixed to the escutcheon 22; a knob shell 23 forming the major portion of the knob proper, and rotatable about, and having a bearing on, the cap piece 20; a spindle 24 carried by the knob shell; and a thimble 25 fixed to the escutcheon, and through which said spindle extends. The pin tumbler lock 21 comprises a casing 26 secured to, or integral with, the cap piece 20, and it is likewise provided with a pin tumbler extension 27, and with a key plug 28, which rotates in an opening in the cap piece. At opposite sides of the casing 26 of the pin tumbler lock, the latter is provided with rearwardly projecting lugs 29, having screw holes 30, which engage the threaded ends of screws 31 screwed into the pin tumbler lock and fixing it rigidly to the escutcheon 22, as shown in Fig. 5. The screws 31 also pass through openings 32 in a flange 33 at the outer end of the thimble 25, and the heads 34 of said screws are located at the inner face of the escutcheon, with the shanks of the screws passing through holes 35 in the escutcheon, whereby the pin tumbler lock and the thimble are both rigidly secured to the escutcheon. 90

The cap piece 20 is provided at its periphery with a rabbet 20^a which forms a fixed bearing for the correspondingly shaped front edge 23^a of the knob shell 23, which 105

knob shell incloses, and is rotatable about, the portion of the pin tumbler lock extending rearwardly from the cap piece. The shell 23 is connected with the knob spindle 24 by a flange or web 36, which preferably joins the shell and the spindle in an integral manner. The web or flange 36 is interposed between the flange 33 of the thimble and the rear end of the case of the pin tumbler lock, and is provided with arcuate slots 37, which clear the lugs 29, and permit the knob to have a limited turning movement. By referring to Fig. 6, it will be noted that the lugs 29 and slots 37 are shaped to conform to each other, but that the lugs are considerably shorter than the corresponding slots. In the normal position of the parts, as shown in Fig. 6, the lugs will be in the middle portions of the respective slots so that the knob shell may be turned to a certain extent in either direction. The screws 31 not only attach the pin tumbler lock and the thimble to the escutcheon, but they also secure the knob spindle 24 rotatively in an opening 38 in the escutcheon by clamping against the inner face of the escutcheon the sectional retaining plate 39, which extends into an annular groove 40 in the knob shank, as shown in Figs. 4 and 5.

The inner end of the knob spindle 24 is provided with a polygonal portion 41 adapted to fit a corresponding polygonal opening in a hub or roll-back 42, whereby the bolt 35 (not shown) is adapted to be retracted in any preferred manner. Adjacent the roll-back 42 is a second roll-back 43 adapted to be operated by the pin tumbler lock, for which purpose said roll-back 43 is suitably connected to a key rod 44 extending rearwardly from, and rotatable by the key plug 28. The outer end of the key rod is provided with a head 45, which is detachably connected with the key plug preferably in the following manner. At the rear end of the key plug, the latter has attached thereto by screws 46, a cap or washer 47 having an interrupted annular flange presenting notches or seats in which the respective ends 50 of the head 45 are adapted to be held in such a manner that the key plug and the key rod will be interlocked to rotate together. The head 45 is loosely seated in the seat on the rear end of the key plug, and is held therein by the knob spindle 24, which is provided with an annular shoulder 48, that overlies the head 45 when the parts are assembled, and holds the head to its seat. The shoulder 48 of the knob spindle forms the back or bottom of a circular recess or seat into which the cap or disk 47 extends, and in which it is seated in the manner shown in Figs. 4 and 5.

The operation of the device is substantially as follows: When the hub 42 of the knob spindle 24 is not dogged by the usual

night latch mechanism (not shown) the knob shell 23 may be turned in either direction to an extent necessary to actuate the latch mechanism. A full rotation of the knob shell, however, is prevented by the engagement of the lugs 29 with the edges of the respective slots 37. The cap piece 20 of the knob and the pin tumbler lock remain stationary at all times. When the knob spindle 24 is rendered immovable, the lock may be actuated by a key inserted in the keyway of the pin tumbler lock, and adapted to release the key plug, which, in turning, will operate the key rod and its roll-back in an obvious manner. The facility of manipulating the knob is not impaired by having the section 20 thereof stationary as the movable part is so located as to be readily grasped and turned.

The knob shell is so assembled relatively to the pin tumbler lock as to hold the key rod in operative relation to the latter. The main parts of the structure may be readily detached by removing the screws 34 from the inside of the escutcheon, and disengaging the retaining plate 39 from the knob spindle, whereupon the pin tumbler lock, the knob shell, and the thimble will be immediately released from each other. The lock may be readily assembled by a reversal of this operation, the pin tumbler lock, knob proper, and thimble being fitted together in the manner shown in Fig. 5 so that the screws 31 in being screwed into the pin tumbler lock from the inner face of the escutcheon will hold the parts firmly together and to the escutcheon.

Of course, I have not attempted to illustrate or describe the various modifications of the construction which may be adopted within the scope of the appended claims.

What I claim is:

1. The combination of an escutcheon, a pin tumbler lock fixed to the same, and a bolt operating member rotatable about said pin tumbler lock; substantially as described.

2. The combination of an escutcheon, a pin tumbler lock fixed to the same, and a bolt operating member rotatable about said pin tumbler lock, and passing through the escutcheon; substantially as described.

3. The combination with an escutcheon, of a pin tumbler lock secured thereto and rigid therewith, and a knob section inclosing said pin tumbler lock and rotatable relatively to the same; substantially as described.

4. The combination with an escutcheon, of a pin tumbler lock secured to and rigid with said escutcheon and located in front of said escutcheon, and a knob shell having a rotatable bearing on said pin tumbler lock; substantially as described.

5. The combination with an escutcheon, of a pin tumbler lock having a fixed part with radial pin tumblers, and a movable key plug,

means for securing the fixed part of said pin tumbler lock to said escutcheon at the front of the latter, and a knob shell rotatable about said pin tumbler lock; substantially as described.

6. The combination of a plate, a pin tumbler lock having radial pin tumblers, rigidly secured to said plate at one side of the

10 same, said lock having a rotary key plug coöoperating with said pin tumblers, a knob shell having a rotatable bearing on the fixed part of said pin tumbler lock at one side of said plate, a bolt-operating member extending from said key plug through said plate 15 to the other side thereof, and a second bolt-operating member connected with said knob shell and extending through said plate; substantially as described.

7. The combination with an escutcheon, of 20 a two-part knob, one part of said knob carrying a pin tumbler lock and being rigid with the escutcheon, the other part of the knob being rotatable relatively to the first named part, and having a spindle passing 25 through the escutcheon, a thimble surrounding said spindle, and a single means for securing the thimble and the fixed part of the knob to the escutcheon; substantially as described.

30 8. The combination with an escutcheon, of a thimble secured thereto, a pin tumbler lock rigid with said thimble, and a knob section extending and rotatable about said pin tumbler lock, and having a spindle passing 35 through said thimble and the escutcheon; substantially as described.

9. The combination with an escutcheon, of 40 a knob cap piece, a pin tumbler lock carried by said cap piece, a thimble, means for securing the thimble and pin tumbler lock rigidly to the escutcheon, and a knob section having a rotatable bearing on said cap piece, and provided with a spindle passing 45 through the escutcheon; substantially as described.

10. The combination with an escutcheon, of a pin tumbler lock fixed to said escutcheon, a knob shell rotatable about said pin tumbler lock, and having a spindle passing 50 through the escutcheon, and means associated with said pin tumbler lock to limit the turning movement of said spindle; substantially as described.

11. In a knob lock, the combination of a 55 knob section, a pin tumbler lock carried thereby, and having a key plug, a key rod, and a second knob section holding said key rod in operative relation to said key plug; substantially as described.

60 12. In a knob lock, the combination of a knob section, a pin tumbler lock secured thereto, and having a key plug, said key plug being provided at its rear end with a seat, a key rod having a head, and a second 65 knob section having means overlying the

head of said key rod, and holding it in said seat; substantially as described.

13. The combination with an escutcheon, of a knob comprising two parts which are fixed and movable respectively in regard to 70 said escutcheon, and a lock carried by the fixed part of the knob; substantially as described.

14. The combination of an escutcheon, and a knob having a cap rigid with the escutcheon, and a rotatable operating shell; 75 substantially as described.

15. The combination of an escutcheon and a knob having a cap rigid with the escutcheon, and a rotatable operating shell 80 bearing on said cap; substantially as described.

16. The combination of an escutcheon, a knob cap having a bearing, means for securing said cap to said escutcheon, and a 85 rotary knob shell having a spindle passing through the escutcheon, and provided with a part engaging said cap bearing; substantially as described.

17. The combination of an escutcheon, a 90 knob cap fixed to the escutcheon having a peripheral bearing, and a rotary knob shell having a rim engaging said bearing; substantially as described.

18. The combination of an escutcheon, a 95 thimble secured thereto, a lock rigid with said thimble, and a knob section extending and rotatable about said lock; substantially as described.

19. The combination of two knob sections, 100 a lock in one section having a key plug, a separate key rod in the other section, and means for holding the key plug and key rod in operative connection with each other by the assemblage of said knob sections; substantially as described.

20. The combination of an escutcheon, a pin tumbler lock, means for securing said pin tumbler lock rigidly to said escutcheon at some distance in front of the escutcheon, 110 a member rotatably mounted on said pin tumbler lock and passing through said escutcheon, and bolt-operating means carried by said member at the inner face of the escutcheon; substantially as described.

21. The combination of an escutcheon, a pin tumbler lock, means for securing said pin tumbler lock rigidly to said escutcheon, 115 a bolt-operating member inclosing said pin tumbler lock and rotatable about the same, 120 and having a spindle extending through the escutcheon, and a key rod connected with said pin tumbler lock, and extending through said spindle; substantially as described.

22. The combination of an escutcheon, a pin tumbler lock secured thereto and rigid therewith, a cap fixed to said lock and constituting a knob section rigid with the escutcheon, and a second knob section inclos- 125

ing said pin tumbler lock and rotatable relatively to the same and to the escutcheon; substantially as described.

23. In a lock, the combination of an escutcheon, a thimble, a pin tumbler lock, a rotary bolt-operating member inclosing said pin tumbler lock, and having a spindle extending through said escutcheon, plates for securing said spindle in said escutcheon, and 5 screws passing through said plates, the escutcheon, the thimble, and into said pin tumbler lock; and holding all of said parts in assembled relation; substantially as described.
- 10

24. In a lock, the combination of an escutcheon, a lock at the outside of the escutcheon, screws for securing said lock rigidly to said escutcheon, and a rotatable bolt operating member surrounding said lock and passing through the escutcheon; 15 substantially as described.

In witness whereof, I have hereunto set my hand on the 24 day of January, 1914.

JOHN H. SHAW.
